UNITED STATES PATENT OFFICE

LAWRENCE P. DWYER, OF CHICAGO, ILLINOIS, ASSIGNOR TO C. A. DUNHAM COMPANY,
OF MARSHALLTOWN, IOWA. A CORPORATION OF IOWA

RADIATOR CONSTRUCTION

Application filed October 29, 1925. Serial No. 65,525.

This invention relates generally to heat exchange and pertains particularly to an improved construction of radiating units for use in effecting exchange of heat between fluids of different temperatures. It finds special applicability in installations for heating or cooling air which is circulated for the ventilating of buildings and the like.

The principal considerations in apparatus 10 of this type are economy in cost, efficiency in effecting the exchange of heat, facility and adaptability of installation, and durability, which includes ability to withstand operating pressures and temperature variations 15 without leakage, and facility of repair.

It is the general purpose of the present invention to attain these several advantages to a maximum degree.

One of the specific objects is the provision 20 of a construction in which the radiating elements may be of very thin or light metal and of extensive length, easily assembled, both in manufacture and in repair, and effectively sealed or secured in such fashion 25 as to avoid distortion of the structure or deterioration of the joints and the opening of leaks incident to prolonged use, temperature variations, pressure of the contained fluid and structural stresses or strains.

30 Another object is the provision of a construction which will facilitate draining of the unit in any of a number of positions, thus rendering it available for installation in a wide variety of situations.

35 A further object is the provision of a construction containing radiating elements of very thin or light weight metal and particularly qualified to facilitate the rapid circulation of the external fluid in contact with 40 them.

Other and further objects of the invention will be pointed out hereinafter, indicated in the appended claims, or will be obvious to one skilled in the art upon an understanding 45 of the present disclosure.

For the purpose of this application I have elected to show and describe herein one form of construction in which the invention may be embodied, but it is to be understood that 50 the same is presented for illustration only,

and is not to be construed as imposing any unnecessary limitations on the scope of the invention as hereinafter claimed.

In the accompanying drawing forming a 55 part of this specification,

Fig. 1 is a side view of the radiator unit, parts being broken away,

Fig. 2 is a sectional view taken substantially on line 2—2 of Fig. 1,

Fig. 3 is an enlarged detail showing the 60 joint connection of a radiating element, and

Fig. 4 is a cross sectional view of a radiating element.

The art recognizes the advantages attained 65 in the use of thin walled radiating elements made of materials having a high heat conductive factor, it being well understood that such elements contribute to the rapid exchange of heat between the contained fluid circulated 70 within them and an external fluid in contact with their outer surfaces. The use of these thin walled or light radiating elements is attended, however, with serious mechanical difficulties in the mounting or coupling of such elements with the necessary headers, manifolds or supply conduits. These mechanical 75 difficulties obtain both in manufacture of the appliances and in their operation. In the manufacture, it is extremely difficult to accomplish economically the assembling of a 80 considerable number of these light elements with the necessary headers and the forming of tight joints which will withstand prolonged or trying usage. The installation of 85 the appliances requires very careful handling of them in order to avoid the straining of the joints and watchfulness must be exercised in their operation for the detection of leaks which are likely to result at any time due to 90 the relative insecurity of the joints. In some commercial forms the joints are made by soldering the ends of the light radiating elements to the headers, but such joints are not reliable, as they are not strong and the solder tends to 95 deteriorate with use and with changes in temperature. Such constructions, moreover, are very difficult to repair. In other constructions attempts have been made to utilize various forms of screw or clamping couplings, but difficulties were encountered in assem-

55

bling, due to the likelihood of twisting or distorting the light radiating elements in turning up the couplings. Such constructions, moreover, have been of such nature that their 5 cost is prohibitive for general commercial usage.

The present invention contemplates a construction in which screw threaded clamping 10 couplings are employed, the structure being so organized that assembly may be accomplished with facility and in such fashion that distortion of the light radiating elements is avoided. The nature of the invention will be more quickly understood by a detailed consideration of the embodiment illustrated. In the drawing, the numerals 10 designate headers 15 suitably equipped for connection to supply and withdrawal conduits, as by means of the threaded flanges 10^a. The headers may be formed in any desired shape or fashion, as of cast metal, and afford distributing chambers 10^b. The wall 10^c of the header constitutes a mounting wall for attachment of the radiating elements. This wall is pierced at 20 properly spaced intervals by apertures 10^d which extend through nipples 10^e projecting from the wall 10^c. These nipples have their outer ends tapered to form conic external surfaces, and their peripheral walls screw 25 threaded. There are two of these headers employed in each unit, one as a supply header and the other as a withdrawal header, said headers being arranged for connection to the opposite ends of the radiating elements or 30 tubes 11. These headers are designed as rights and lefts, differing in the particular that the screw threads on the nipples 10^e on the rights run in the opposite direction to those of the lefts. Suitable clamping nuts 12 35 are provided, adapted for thread engagement with the threaded nipples of the respective headers. These nuts have internal conic clamping surfaces 12^a complementary to the conic ends of the nipples, and are suitably formed, as with spanner notches 12^b, for 40 engagement by a tool for turning them up.

The tubes or radiating elements 11 are formed of thin material, such as light copper 45 seamless drawn tubing, provided externally with radiating fins 11^a brazed directly to their outer surfaces. For a space adjacent the ends of the tubes, they are left bare of fins to afford room for application of the clamping nuts. After the nuts are placed on the ends of the 50 tubes, a left hand nut at one end and a right hand nut at the other end of each tube, the end portions of the tubes are flared or swaged outwardly to a form and size adapting them to seat on the tapering ends of the nipples 55 10^e. The tubes are assembled between the headers, the right hand nuts all at one end and the left hand nuts at the other, and their flared ends fitted on the ends of the nipples 60 of the respective headers. The nuts are then 65 turned up so as to clamp the flared ends of

the tubes firmly between the complementary conic surfaces of the nipples and the nuts. Due to the arrangement described, the turning up of the nuts may be accomplished without twisting the light tubes, as both of the 70 nuts on each tube are rotated in the same direction about the axis of the tube as they are turned up. Due to this feature, the nuts may be turned up very tightly so as to form absolutely tight joints between the tubes and 75 the headers, affording a connection which allows the tubes a desirable flexibility relative to the header without opening the joints or exerting injurious strains on the connections. Individual radiating elements may be removed and replaced as desired, as the elasticity of the tubes permits their being flexed to the degree requisite to remove their flared ends from the nipples or to engage them 80 thereon, when the nuts are backed off. 85

Advantage in efficiency may be gained by the use of radiating elements having their intermediate portions of ovaloid or stream-line cross sectional form, as illustrated in Fig. 4. An element having such a cross sectional form 90 is effective in decreasing resistance to circulation of the external fluid and in securing more extensive and intimate contact of the fluid with the tube. My improved construction is of particular advantage in connection 95 with radiating elements of this type because of the fact that it facilitates the accurate setting of the tubes with respect to the direction of flow of the external fluid. In the use of radiating elements in which the radiating fins 100 are applied as a continuous spiral flange, the tube is afforded substantial reinforcement by the flange. It has been found that this has the effect of localizing at the ends of the tube any twisting resulting from the turning up of the nuts, with the result that the tubes have been weakened and distorted to an increased extent at the joints and in the locations where their strength and integrity are most highly important. My improved construction, therefore, wherein the twisting 110 tendency is avoided, is of additional utility and advantage when radiating elements of this type are used. Considerations of drainage and of internal and external circulating 115 efficiency render a straight tube of distinct advantage over one of tortuous or spiral form, and the use of my construction is of particular value where straight tubes are used, as they are more susceptible to injury from 120 twisting than are tubes of the other description. The construction is also of distinct advantage in installations in which the radiating elements are of exceptional length, as the strength of the joints qualifies them to withstand the additional stresses induced by the linear expansion and contraction of the elements with changes of temperature. The security of the joints and elimination of twisting distortion qualifies a radiator of this con-

struction to withstand internal and external fluid pressures effectively, and contributes to its eligibility for installation in any position, whether horizontal or upright, or with the 5 headers at the sides or at the top and bottom.

What I claim is:

1. A radiator construction comprising 10 headers, radiator tubes having communication at their ends with the headers, and clamping nuts for joining the tubes to the headers, said nuts having portions for clamping engagement with the tubes and screw thread engagement with the headers, the nuts cooperating with a tube being rotatable in 15 the same direction about the axis thereof to effect their clamping engagement therewith.

2. A radiator construction comprising radiating tubes having thin and flexible walls, headers communicating with the tubes at opposite ends thereof, clamping nuts having 20 screw threaded engagement with the headers to effect clamping engagement with the tubes, one of the headers having right hand screw threads and the other having left hand screw 25 threads, for cooperation with the clamping nuts at respective ends of the tubes.

3. A radiator construction comprising a pair of headers, provided with nipples, the nipples of one of the headers being provided 30 with right hand screw threads and the nipples on the other header being provided with left hand screw threads, radiating tubes having communication at their opposite ends with the respective headers, said radiating tubes 35 having thin flexible walls seating at their ends on the header nipples, and clamping nuts having threaded engagement with the nipples and clamping engagement with the tube walls to secure the tubes to the headers.

40 4. A radiator construction comprising headers, radiating tubes communicating at their opposite ends with respective headers, said radiating tubes having thin flexible walls, and screw threaded clamping members 45 securing the tubes to the headers, said clamping members being movable on their threads in opposite directions longitudinally of the tubes by rotation in the same direction about the axis of the tubes.

50 5. A radiator construction comprising headers, radiating tubes communicating at their opposite ends with respective headers, said radiating tubes having thin flexible walls, and screw threaded clamping members 55 securing the tubes to the headers, the clamping members for a tube being rotatable in the same direction about the axis thereof to secure the tube to the header.

60 6. A radiator construction comprising radiating tubes having thin flexible walls and radiating fins extending from the walls, the wall portions adjacent the ends of the tubes being bare of fins, headers communicating with opposite ends of the tubes, and clamping nuts rotatable on the bare end portions 65

of the tubes and having screw thread engagement with the headers to clamp and seal the tubes thereto, the nuts on a tube being rotatable in the same direction for clamping the tube to the headers.

70 7. A radiator construction comprising radiating tubes having thin flexible walls, the end portions of the tubes being substantially circular in cross section and the intermediate portions of the tubes having an ovaloid cross 75 sectional form, headers communicating with the ends of the tubes, and nuts rotatable in the same direction on the end portions of the tubes for clamping them in sealed connection with the headers.

80 8. A radiator construction comprising radiating tubes having thin flexible walls, the end portions of which are substantially circular in cross section and the intermediate portions of ovaloid cross section, radiating 85 fins secured in contact with the intermediate portion, headers, and nuts rotatable on the end portions in the same direction for clamping them in sealed connection with the headers.

90 In testimony whereof I have hereunto subscribed my name.

LAWRENCE P. DWYER.
